UNITED STATES PATENT OFFICE.

JAMES R. McGEE, OF MILWAUKEE, WISCONSIN.

AUTOMATIC RAILWAY-GATE.

1,389,256.

Specification of Letters Patent. Patented Aug. 30, 1921.

Application filed January 24, 1921. Serial No. 439,554.

To all whom it may concern:

Be it known that I, JAMES R. McGEE, a citizen of the United States, and resident of Milwaukee, in the county of Milwaukee and State of Wisconsin, have invented certain new and useful Improvements in Automatic Railway-Gates; and I do hereby declare that the following is a full, clear, and exact description thereof.

10 This invention relates to an improved automatic railway gate for use at grade crossings, and is designed more particularly as an improvement on the structure shown in the United States Patent No. 1356924, granted October 26, 1920, to Joseph Kiss and James R. McGee.

15 The object of the present invention is to provide improved means for connecting the sections of the gate at one side of the crossing to each other, and to the corresponding sections of the gate at the other side of the crossing, so that all four sections may operate in unison.

20 A further object of the invention is to provide an improved means for connecting the gate sections to the operating means.

25 A still further object of the invention is to provide improved means by which the operating mechanism is thrown into operation.

30 Referring to the drawings, which form a part of this specification, Figure 1 is a side elevation of the gate at one side of the crossing, and showing partly in section, means for operating same.

Fig. 2 is a vertical sectional view taken at right angles to the plane of Fig. 1.

35 Fig. 3 is a diagrammatic view showing the means by which the operating mechanism is thrown into operation, and

40 Fig. 4 is a diagrammatic view showing the location of the gates with respect to the crossing.

45 Referring now in detail to the drawings, the gate at each side of the crossing comprises two sections 6 and 7. These sections are in the form of lazy tongs, supported by the posts 8 and 9 respectively by means of the fixed blocks 10 and 11 and the slidable blocks 12 and 13.

50 At one side of the gate one arm of the lazy tongs which is pivoted to the fixed block, is extended beyond its pivot as at 14 to provide a lever by which the lazy tongs may be advanced and retracted.

A link 15 is pivoted at one end to the lever

14, and at the other end is pivotally connected to the link 16 and to the rock arm 17 which is mounted on a rock shaft 18. The rock shaft 18 extends to the other side 60 of the crossing, where it is provided with a similar rock arm 17' which is operatively connected to the lazy tongs 7' which are supported on the post 9' opposite the post 9. A similar post 8' and lazy tongs 6' are also 65 provided at the other side of the crossing opposite the post 8 as shown in Fig. 4, wherein T indicates the railroad track, and H indicates the highway crossing the same.

70 It will be noted that the link 15 and rock arm 17 form a toggle which, as it is extended and contracted, operates to advance and retract the lazy tongs. This operation of the toggle is effected by advancing and retracting the link 16, this movement being 75 accomplished by means of the reciprocable arm 19, which is pivotally connected with the link 16 and is carried on the threaded rod 20 which is rotated in either direction by means of the worm gearing 21 and the 80 motor M.

75 The reciprocating arm 19 is connected to a rod 22 which is slidably mounted in the sleeve 23, which extends under ground to the other side of the gateway. The rod 22 85 carries at its other end an arm 24 similar to the arm 19, which is connected by a link 25 with the toggle formed by a link 26 and rock arm 27. The link 26 is pivotally connected to the lever 28, which is a continuation 90 of one of the links of the lazy tongs 6. The rock arm 27 is mounted on the rock shaft 29, which extends to the other side of the crossing, and is operatively connected to the lazy tongs 6'. 95

Thus it will be seen that when the motor M is operated in one direction all four pairs of lazy tongs will be simultaneously advanced, and when the motor is operated in the other direction the same will be retracted.

100 The means for throwing the closing mechanism into operation comprises a trip arm 30 which is located on the railroad track and projects upwardly into the path of some 105 portion of the railway vehicle. A similar trip arm 30' is provided on the track on the other side of the crossing. As the train approaches the crossing the trip arm 30 or 30' is rocked to temporarily close the switch 110 31 or 31'. This closes the circuit from the source of electric energy 32 through the

magnetic coil 33 wire 34 or 34', switch 31 or 31', wire 35 or 35', thence through the wires 36 and 37 back to the source. As soon as the magnetic coil 33 is energized the 5 switch 38 is closed. The circuit then passes from the source 32 through the switch 38, wire 39, switch 40, wire 41, motor M, wire 42 through the other pole of switch 38 and through wire 37 back to the source. The 10 motor is thus operated to rotate the screw 20 and the arm 19 is advanced to the right as shown in Fig. 3.

The depending lug 43 which has been holding the switch 44 open thus allows the 15 switch 44 to close and by the time the gate has been closed the lug 43 reaches the switch 40 and opens the same, thus discontinuing the operation of the motor.

When the train has passed the crossing 20 and reached the trip arm 30 or 30' on the other side, said trip arm is thrown to close the switch 45 or 45'. A current is then allowed to pass from the source 46 through wire 47, magnetic coil 48, wire 49, thence 25 through wire 50, switch 45, wire 51 or through the switch 45' thence through wires 52 and 53, back to the source. This energizes the magnetic coil 48 and closes the switch 54. Current then passes through the 30 wire 55, switch 44, wire 56, thence through the motor M and wire 57 through the other pole of the switch 54 back to the source. This operates the motor M in the opposite direction and opens the gates.

35 I claim as my invention:

1. In combination with a gate comprising a pair of lazy tongs, a toggle having one link operatively connected to one arm of the lazy tongs, the other link being pivotally 40 connected to a fixed point, a reciprocable arm having a link connection with the toggle and means for reciprocating said arm to operate said toggle to advance and retract said lazy tongs.

45 2. In combination with a gate comprising oppositely disposed pairs of lazy tongs, a

toggle at each side of the opening to be closed, one link of each toggle being pivotally connected to a fixed point, the other link of the toggle being operatively connected with one arm of the lazy tongs, a reciprocable rod and a pair of arms carried thereby, means for reciprocating said rod and arms, and means connecting said arms to the toggles for operating the same to advance and retract said lazy tongs. 50 55

3. In combination with a gate comprising a pair of lazy tongs, a toggle having one link operatively connected to one arm of the lazy tongs, a rock shaft on which the other link of the toggle is mounted, a similar gate at the opposite side of the crossing and a toggle for operating the same, one link of said last named toggle being mounted on the other end of said rock shaft, a reciprocable arm having a link connection with one of said toggles and means for reciprocating said arm to operate said toggles to advance and retract said lazy tongs. 60 65

4. In combination with a gate comprising oppositely disposed pairs of lazy tongs, a toggle at each side of the openings to be closed, one link of said toggle being operatively connected with one arm of the corresponding pair of lazy tongs, a rock shaft 70 at each side of the opening on which the other link of the toggle is mounted, a similar gate at the opposite side of the crossing, and toggles for operating the same, said last named toggles each having one link mounted on the other end of one of said rock shafts, a reciprocal arm having a link connecting it with one of said toggles, and means for reciprocating said arm to operate said toggles to advance or retract 75 80 85 said lazy tongs.

In testimony that I claim the foregoing I have hereunto set my hand at Milwaukee, in the county of Milwaukee and State of Wisconsin.

JAMES R. McGEE.
